Primary Examiner — Vy N Koenig(74) *Attorney, Agent, or Firm* — ScienBiziP, P.C.(57) **CLAIM**

The ornamental design for a gimbal, as shown and described.

DESCRIPTION

FIG. 1 is a top front perspective view of a gimbal showing my design;

FIG. 2 is a top rear perspective of the gimbal of FIG. 1; FIG. 3 is a front elevation view of the gimbal of FIG. 1; FIG. 4 is a rear elevation view of the gimbal of FIG. 1; FIG. 5 is a left side elevation view of the gimbal of FIG. 1; FIG. 6 is a right side elevation view of the gimbal of FIG. 1;

FIG. 7 is a top plan view of the gimbal of FIG. 1; and, FIG. 8 is a bottom plan view of the gimbal of FIG. 1. The broken lines in the drawings are for illustrating unclaimed portions of the gimbal, and form no part of the claimed design.

1 Claim, 8 Drawing Sheets(56)
